UNITED STATES PATENT OFFICE.

GEOERGE FOSTER REZNOR, OF MERCER, PENNSYLVANIA.

WALL-HEATER.

1,169,466.

Specification of Letters Patent.

Patented Sept. 1, 1914.

Application filed August 2, 1913. Serial No. 782,706.

To all whom it may concern:

Be it known that I, GEORGE FOSTER REZNOR, a citizen of the United States, and a resident of Mercer, in the county of Mercer and State of Pennsylvania, have invented 5 a new and Improved Wall-Heater, of which the following is a full, clear, and exact description.

My invention more particularly relates to 10 gas heaters of the type known as wall-heaters, and is especially intended for use in bath rooms.

It is a design of my invention to provide a heater of the indicated character the body 15 and frame of which will be kept below a temperature at all liable to set fire to the walls in which the heater is installed.

It is a further design of the invention to construct a heater that may be fitted in any 20 wall without special preparation of the wall and without the necessity of lining the wall opening with fire brick, asbestos, or any other heat-resisting materials.

It is a further design of the invention to 25 provide a novel means for fastening the heater to the wall.

The invention furthermore has for its design to produce a heater in which the elements are arranged and supported in a manner 30 permitting of the heater being readily assembled or dismembered, and in which access may be conveniently had to the various parts for the purpose of cleansing or repair.

The distinguishing features of my invention, 35 and the important structural elements characterizing the practical embodiment which is illustrated as an example, will be more particularly explained in the specific description following.

Reference is to be had to the accompanying 40 drawings forming a part of this specification, in which similar characters of reference indicate corresponding parts in all the views.

Figure 1 is a front elevation of a wall 45 heater embodying my invention; Fig. 2 is a vertical transverse section; Fig. 3 is a vertical section taken on the line 3-3 of Fig. 2, the reflector hereinafter referred to being omitted; and Fig. 4 is a horizontal section on the line 4-4 of Fig. 2.

In constructing a heater in accordance 50 with the illustrated example, a box-like body 10 is formed of general rectangular shape, desirably having double walls with a suitable filling of heat insulating material. To

the open front of the box a main frame 11 is secured by stove bolts 12, or their equivalent, the said frame being flanged to extend laterally on all sides of the front, and rearwardly, as at 13, so that when the body 10 is inserted in a recess in the wall A, the rear edge of the front flange 13 will contact with the face of the wall.

To fasten the heater in the wall recess, 65 wires 14 are employed at each side, the said wires being given a turn or two around nails 15 or the like driven into the studding at each side of the recess, the wires being returned on themselves and then carried 70 forwardly through holes in the flange 13, the ends of the wires being twisted as clearly shown in Fig. 3. The holes 16 are preferably produced in depressed portions 17 (see Fig. 4) whereby the twisted ends 14^a will 75 be within the general plane of the surface of the flange 13. A facing frame 18 is detachably secured to the front frame 11, in a suitable manner, such as by means of hooks 19 (Fig. 2) on the rear edge of the said facing 80 frame at the top, and engaging suitable holes in the main frame 11, and by a screw 19^a (Fig. 1) at the bottom. Desirably also, there is detachably secured to the facing frame 18, a cornice or cornice-like transverse member 20 of ornamental form, which 85 gives a finish to the front of the heater at the top of the exposed open front, through which the reflector hereinafter referred to appears. In the illustrated form the cornice 20 has rearwardly projecting hooks 21 which engage over lugs 22 on the facing frame 18.

The burner may consist of a transverse tube or length of pipe 23, having a longitudinal series of forwardly and downwardly disposed nipples or tips 24 having jet orifices for the gas. The burner tube is shown as disposed transversely at the upper end of a gas pipe 25 having suitable connection 95 with a supply pipe 26, there being a valve suitably located between the source of supply and the burner tube, the valve stem 27 in the present instance extending forwardly through the main frame 11 and through an 100 opening 18^a in the facing frame 18.

The heater includes a reflector below the burner tube, said reflector comprising the corrugated bottom 28, which curves upwardly and rearwardly, and sides 29, the 110 said reflector being suitably secured to and supported by the facing frame 18 so as to

be detachable bodily with the said frame. The upper end of the combined bottom and back 28 of the reflector extends as at 28^a, above the top edges 29^a of the sides 29, at 6 the back of the burner tube 23, as best shown in Fig. 2.

Referring particularly to Figs. 2 and 3, the reflector it will be apparent, is of such dimensions as to be spaced from the body 10 10 of the heater, thereby providing a clear space around the bottom and sides of the reflector, and said reflector is considerably below the top of the heater body. Associated with the reflector is a hood, the top 30 of which inclines upwardly and forwardly and has a depending apron 31 extending around the sides and back of the top. The top 30 of the hood is spaced from the reflector and from the burner tube 23, and the apron 31 15 20 of the hood is spaced from the reflector at the sides and back. The hood is supported independently of the reflector, being detachably secured to the body 10, preferably by hanger brackets 32, the upturned ends of 25 which are secured by bolts 33 or the like to the body, and the bracket 32 is bolted or otherwise fastened, as at 32^a, to the top 30.

By the described arrangement of the reflector and hood relatively to the box-like 30 body 10, an air conducting space 34 is produced between the apron 31 and the reflector, the said air space communicating at the top of the reflector with what may be termed the burner chamber or open front of 35 the hood, so that a current of air will pass rearwardly and upwardly from below the reflector and to and over the latter and along the under side of the top 30 of the hood, above the burner tube 23 to the front of the 40 heater. The cornice 20 is more or less open and forms the outlet for the air passing forwardly beneath the top of the hood. There is furthermore, formed an air chamber 35 between the apron 31 of the hood and the back of the box-like body 10, and this space extends upwardly and communicates with the larger space above the top 30 of the hood, and between the same and the top of the box 10.

At the front of the space above the hood top 30 the facing plate 18 is formed with openings 18^b so that cool air entering between the reflector bottom 28 and the bottom of box 10 from the front, through the 50 openings 18^a, will divide a current passing not only to the space 34 in front of the apron 31, but to and through the surrounding space 35 behind the said apron, thence over the top 30 of the hood through the 55 main frame 11 at the front of the body, and thence through the openings 18^b in the facing frame 18, the result being that there are two distinct air chambers producing cooling air currents both above and below the top 60 65 30 of the hood, which will insure that the

body and frame of the heater will be maintained at a temperature involving no possible danger of the wall elements being set on fire. A further air chamber is provided to induce an additional cooling air current at 70 the exterior of the body 10. Thus a shell 36 is disposed outside of the body, which extends over the top thereof and downwardly preferably at the sides and back of the body, to a distance below the horizontal center of 75 the heater. The shell may be secured in place in any suitable manner, there being screw bolts 37 usually employed in practice, said bolts passing through the shell and through the body 10. The shell is sufficiently spaced from the outer surface of the body to provide an intervening chamber 38 through which air may pass upwardly around and over the body, through the front frame 11 which is provided in the flange 13 thereof with openings 13^b for the ingress and egress of the air.

A heater constructed as described, overcomes a great difficulty previously existing in fitting the heater to a wall without special preparation with a view to lining the wall opening with fire-resisting materials. It will be clear also that by the described construction, ready access can be had to any of the parts and their cleansing, repair or 90 renewal be conveniently effected.

It is to be understood that the office of the elements 28, 29 in the present structure is not primarily to reflect the flames of the jets, but to reflect the heat out into the room 100 and to direct the air at the under side upwardly and rearwardly to the air chambers 34, 35.

Having thus described my invention, I claim as new, and desire to secure by Letters Patent:

1. In a heater of the character described, a box-like body open at the front, a hood supported in the body below the top thereof and spaced from the back of the body, the intervening air space between the hood and body having an inlet at the bottom and having an outlet through the open front of the body, heating means in the body beneath the hood, and an exterior shell extending over the body at the top and depending at the sides and back of the body, there being an intervening space between the body and shell, the space between the body and shell being open at the bottom and having an outlet at the front of the heater.

2. In a heater of the character described, a box-like body open at the front and adapted to be received in a wall recess, a main frame extending around the body at the front, a shell outside the body and spaced therefrom, said shell extending over the top and depending at the sides, the space between the shell and body being open at the bottom for the inlet of air, and the said

main frame having a flange extending rearwardly and outwardly over the front edge of the shell, said flange having an outlet for air from the space between the shell and body, a facing frame supported on the main frame, a hood supported in the body and spaced from the latter, providing an intervening air chamber which is open at the bottom, the said facing frame forming a continuation of the air space between the hood and body and having an outlet for air, and heating means beneath the hood

3. A heater of the character described, a box-like body having an open front, a transverse burner between the top and bottom of the body, a reflector extending upwardly and rearwardly from the front to the burner and terminating at the back of the burner, and means associated with the body and reflector, forming three separate air cham-

bers, open at the bottom, said means comprising a hood above the reflector and below the top of the body, the hood having a top extending to the front of the body and rearwardly beyond the burner and provided with a depending apron, the hood at the top, back and sides being spaced from the body, and a shell outside the body and spaced therefrom at the top, back and sides, the said space between the hood and the body, being separated from the spaces beneath the hood, the said spaces having separate outlets at the front.

In testimony whereof I have signed my name to this specification in the presence of 35 two subscribing witnesses.

GEORGE FOSTER REZNOR.
